UNITED STATES PATENT OFFICE.

ISADORE B. PATZ, OF BALTIMORE, MARYLAND.

DESIGN FOR A NECKTIE.

Application filed August 26, 1922. Serial No. 3,566. Term of patent 3½ years.

To all whom it may concern:

Be it known that I, ISADORE B. PATZ, a citizen of the United States, residing at Baltimore, in the State of Maryland, have invented a new, original, and ornamental Design for Neckties, of which the following is a specification, reference being had to the accompanying drawings, forming part thereof.

I claim:

The ornamental design for a necktie, as shown.

ISADORE B. PATZ.
